UNITED STATES PATENT OFFICE

130,516

DESIGN FOR A TEXTILE FABRIC

Lucien Forestier, Paterson, N. J.

Application October 17, 1941, Serial No. 103,790

Term of patent 3½ years

To all whom it may concern:

Be it known that Lucien Forestier, a citizen of France and resident of Paterson, in the county of Passaic, State of New Jersey, has invented a new, original, and ornamental Design for a Textile Fabric, of which the following is a specification, reference being had to the accompanying drawing, forming part thereof, and in which the figure is a plan view of a piece of textile fabric showing my new design.

The area bounded by the dot, dash lines is a repeat of the design.

I claim:

The ornamental design for a textile fabric, substantially as shown and described.

LUCIEN FORESTIER.
